UNITED STATES PATENT OFFICE.

ROY E. JORDAN, OF NEWARK, NEW JERSEY, ASSIGNOR TO THE MOSAIC TILE COMPANY, A CORPORATION OF OHIO.

DESIGN FOR A PROJECTING TUMBLER HOLDER.

Application filed March 4, 1924. Serial No. 8,819. Term of patent 14 years.

To all whom it may concern:

Be it known that I, Roy E. JORDAN, a citizen of the United States, residing at Newark, county of Essex, and State of New Jersey, have invented a new, original, and ornamental Design for Projecting Tumbler Holder, of which the following is a specification, reference being had to the accompanying drawing, forming part thereof.

Fig. 1 is a perspective view of a projecting tumbler holder embodying my invention;

Fig. 2 is a plan view of said holder;
Fig. 3 is a front elevation thereof; and
Fig. 4 is a side elevation of the same.

I claim:

The ornamental design for a projecting tumbler holder, as shown.

ROY E. JORDAN.
